(57) **CLAIM**

The design for a multimedia storage tray, as shown and described.

DESCRIPTION

FIG. 1 is a perspective view of a multimedia storage tray incorporating the design of my new invention, comprising two identical modular tray components;

FIG. 2 is a top plan view thereof;

FIG. 3 is a bottom plan view thereof;

FIG. 4 is a front elevational view thereof, with the rear elevational view being identical thereto; and,

FIG. 5 is a right-side elevational view thereof, with the left-side elevational view being identical thereto.

The broken lines in FIGS. 1–5 depict the environment of the multimedia storage tray and form no part of the design.
